UNITED STATES PATENT OFFICE.

ELIJAH B. BENHAM, OF PROVIDENCE, RHODE ISLAND.

PITMAN.

SPECIFICATION forming part of Letters Patent No. 395,206, dated December 25, 1888.

Application filed March 22, 1888. Serial No. 268,156. (No model.)

To all whom it may concern:

Be it known that I, ELIJAH B. BENHAM, a citizen of the United States of America, residing at Providence, in the county of Providence and State of Rhode Island, have invented new and useful Improvements in Pitman and Crank Connections, of which the following is a specification.

This invention relates to an improved form of connection between a pitman or connecting rod and a crank or wrist pin or other similar part of a machine particularly applicable for use where several pitman-rods converge to and are engaged with a common crank-pin, as in multiple-cylinder rotary engines, the object thereof being to so form and connect the several pitman-rods to the crank-pin that each may have a considerable length of bearing around the periphery of said pin, whereby the said bearing portions of the several pitman-rods will require and occupy but little lengthwise-extended area on the periphery of the crank-pin, securing an easier, steadier, and more accurate and durable connection than heretofore; and the invention consists in the peculiar formation of each of the several pitman-rods, and in the combination, with the several of the said pitman-rods and the crank-pin, of devices for securing the connection between said pitman-rods and crank-pin, all substantially as will hereinafter more fully appear, and be set forth in the claims.

In the accompanying sheet of drawings the present invention is illustrated as applied in connection with a multiple-cylinder rotary engine or motor, the cylinders of which radiate from a common center, Figure 1 being a central vertical section through the cylinder-head thereof. Fig. 2 is a partial cross-section on the line $\alpha\alpha$, Fig. 1; and Fig. 3 is a view of a pitman-rod formed in accordance with this invention.

In the drawings, A represents the cylinder-head of a multiple-cylinder rotary engine of the character described, comprising eight cylinders, the cutting-plane of the section here given passing through two cylinders, 5 6, radially and oppositely disposed in relation to the axial line of the main shaft B, said cylinders having their axes in a plane intersect-

ing the crank-pin D, carried by said main shaft, transversely and midway of its length.

E represents the pistons in said cylinders, and each piston of the several cylinders has a pitman-rod, G, axially connected thereto in any usual or approved manner.

Each pitman-rod is provided at its end opposite from its piston with a foot, d, having its inner or heel end, f, when in place about the crank-pin, in the central transverse plane of said crank-pin, which is also coincident with the axes of the cylinders, and the alternate pitman-rods are disposed on the crank-pin to project by their feet from said central portion thereof to its outer end—for instance, toward the right—and the relatively intermediate pitman-rods are arranged to project by their feet from said common central portion of the crank-pin toward the opposite end or to the left. The extent of the length of the arc-formed bearing-surface of each foot is determined by the number of such pitman-rods to be employed about and upon a single crank-pin—as, for instance, as shown, where eight pitman-rods are employed, the feet of four thereof about one end portion of the crank-pin and the feet of the other four about the other end portion of said crank-pin. The curved bearing-surface of each foot is an arc embracing a little less than one-quarter of a circle, so that the feet of four pitman-rods may be disposed about the periphery of one end portion of the crank-pin, allowing a little clearance between the feet to enable the edges of said feet to move slightly toward and away from each other under varying directions of the piston forces in different portions of a stroke, and in Fig. 2 the described disposition of the eight pitman-rods about one crank-pin is particularly shown. The said rods, designated by g, have their feet extending to the right, while the relatively intermediate rods have their feet extending to the left.

Each pitman-rod extends perpendicularly from its foot, its one side, m, being in the plane of the heel end f of said foot for a certain distance, when it is widened, as at n, for increased strength, and to enable its inner end to be connected concentrically about the axial portion of the piston.

The angular feet of each series of pitman-
rods are confined in place by a sleeve or collar, M, of an internal size to embrace the outer sides of said feet, and both of said collars at
5 their inner end portions have flanges or right-angled lugs p, which lie by their sides against the outer sides of the pitman-rods, and upon the outer sides of one or more pitman-rods of each series—as, for instance, on the two dia-
10 metrical opposite to each other—a segmental plate, Q, rabbeted at its inner side in an arc line, as at q, is hung by and upon a bolt, t, which passes through the segmental plate which is at one side of the central transverse
15 portion of the crank-pin overlying the flange of one ring, M, to and through the similar segmental plate, Q, overlying the flange of the ring M at the other side of the central trans-
verse portion of the crank-pin, whereby the
20 said rings are held to their confining positions upon the pitman-rod feet for their re-
tention in place about the crank-pin. Instead of supporting two segmental plates, Q, upon a single pitman-rod, one to overlie each
25 flanged ring M, one of said plates Q may be hung upon one pitman for its engagement with one flanged ring, while another thereof
may be hung upon another pitman for an en-
gagement with the other flanged ring, and, in
30 practice, more or less of the said segmental plates may be employed, as desired, although two for each ring M are generally sufficient; and where two segmental plates are supported from a single pitman, as shown in Fig. 1, a
35 washer, v, is disposed about the bolt t between the side of the pitman and the one of said plates to add rigidity and support to the parts.

Preferably, and as seen in Fig. 1, each pit-
40 man-rod foot d, as to its thickness, tapers out-
wardly on its side opposite its arc-shaped
crank-bearing face, and each of the rings M is also made with a corresponding inner flar-
ing or tapering periphery, whereby the wear
45 upon the arc-shaped bearing-faces about and upon the crank-pin may be taken up by draw-
ing the rings M inwardly on the bolts, turning
the nuts thereon.

As shown in the drawings, the crank-pin D
50 is bushed with a loose friction-sleeve, J, the
same constituting a part of the crank-pin, al-
though the same may in some instances be
dispensed with without departing from the
present invention.

55 What I claim as my invention is—

1. In a multiple - cylinder rotary engine comprising a series of radial cylinders, a main shaft, B, having the crank or wrist pin, and a piston for each of said radial cylinders, the
60 combination, with said crank or wrist pin, of a series of pitman-rods each connected with a piston and each consisting of the leg portion, and the segmental foot formed thereupon and extending from one side thereof, provided
65 with an arc-shaped bearing-surface, a portion of said series of pitman-rods being arranged with their feet extending from the central por-

tion of said crank-pin toward one end thereof, and the other portion of said series of pitman-
rods being arranged with their feet extending 70 from said central portion of said crank-pin to-
ward the other end thereof, and independent
collars surrounding the said feet of each se-
ries, substantially as described.

2. In a multiple - cylinder rotary engine 75 comprising a series of radial cylinders, a main shaft, B, having a crank or wrist pin, and a piston for each of said radial cylinders, the combination, with said crank or wrist pin, of a sleeve thereon, and a series of pitman-rods 80 each connected with a piston and each con-
sisting of the leg portion and the segmental
foot formed thereupon and extending from
one side thereof, provided with an arc-shaped
bearing-surface, a portion of said series of 85 pitman-rods being arranged with their feet
extending from the central portion of said
crank-pin toward one end thereof, and the
other series of pitman-rods being arranged
with their feet extending from said central 90 portion of said crank-pin toward the other
end thereof, and independent collars sur-
rounding each series of feet, for the purpose
described.

3. In a multiple - cylinder rotary engine 95 comprising a series of radial cylinders, a main shaft, B, having the crank or wrist pin, and a piston for each of said radial cylinders, the combination, with said crank or wrist pin, of a series of pitman-rods each connected with a 100 piston and each consisting of the leg portion
and the foot formed thereon and extending
from one side thereof, provided with an arc-
shaped bearing - surface and tapering out-
wardly as to its thickness, a portion of said 105 series of pitman - rods being arranged with
their feet extending from the central portion
of said crank-pin toward one end thereof, and
the other portion of said series of pitman-rods
being arranged with their feet extending from 110 said central portion of said crank-pin toward
the other end thereof, and collars provided
with a tapering internal periphery surround-
ing said feet of each series, substantially as
and for the purpose described. 115

4. In a multiple - cylinder rotary engine 120 comprising a series of radial cylinders, a main shaft, B, having the crank or wrist pin, and a piston for each of said radial cylinders, the combination, with said crank or wrist pin, of a series of pitman-rods, each connected with a piston and each consisting of the leg portion 125 and the segmental foot formed thereon and extending from one side thereof, pro-
vided with an arc-shaped bearing-surface, the
said leg portion having its one or outer side
for a portion of its length in the plane of the
heel end thereof and for a portion of its length
widened to extend across said plane, a portion
of said series of pitman-rods being ar- 130 ranged with their feet extending from the central
portion of said crank-pin toward one end
thereof and the other portion of said series of
pitman-rods being arranged with their feet

- extending from said central portion of said crank-pin toward the other end thereof, and independent collars surrounding the said feet of each series, for the purpose described.
5. In a multiple-cylinder rotary engine comprising a series of radial cylinders, a main shaft, B, having the crank or wrist pin, and a piston for each of said cylinders, the combination, with said crank or wrist pin, of a series of pitman-rods, each connected with a piston and each consisting of the leg portion and the foot formed thereupon and extending from one side thereof, provided with an arc-shaped bearing-surface, a portion of said series of pitman-rods being arranged with the feet extending from the central portion of said crank-pin toward one end thereof, and the other portion of said series of pitman-rods being arranged with the feet extending from said central portion of said crank-pin to the other end thereof, and the collars surrounding each series of feet, each collar provided with the flange *p*, and segmental plates *Q*, overlying said collar-flanges, each hung upon one of said pitman-rods, substantially as and for the purpose described.
6. In a multiple-cylinder rotary engine comprising a series of radial cylinders, a main shaft, B, having the crank or wrist pin, and a piston for each of said cylinders, the combination, with said crank or wrist pin, of a sleeve, J, thereon, and a series of pitman-rods, each connected with a piston and each consisting of the leg portion and the foot formed thereupon and extending from one side thereof, provided with an arc-shaped bearing-surface and tapering outwardly as to its thickness, and the said leg portion having its outer side for a portion of its length in the plane of the heel end thereof, and for a portion of its length widened to extend across such plane, a portion of said series of pitman-rods being arranged with their feet extending from the central portion of said crank-pin toward one end thereof, and the other portion of said series of pitman-rods being arranged with their feet extending from said central portion of said crank-pin toward the other end thereof, the collars *M*, one of which surrounds each series of feet, having tapering internal peripheries and provided with the flanges *p*, and rabbeted segmental plates *Q*, overlying said collar-flanges, and the bolts passing through said segmental plates and the pitman-rods, all substantially as and for the purpose described.
7. The combination, with the crank-pin *D*, of a series of pitman-rods, each consisting of the leg portion and the foot formed thereupon and extending from one side thereof, provided with an arc-shaped bearing-surface, a portion of said series of pitman-rods being arranged with the feet extending from the central portion of said crank-pin toward one end thereof, and the other portion of said series of pitman-rods arranged with the feet extending from said central portion of said crank-pin toward the other end thereof, the collars *M*, surrounding each series of feet, each collar provided with the flange *p*, the segmental plates *Q*, hung in pairs on the bolt *t* of one of the pitman-rods and overlying said ring-flanges, and the washers *v*, substantially as described.
